UNITED STATES PATENT OFFICE.

ALBERT J. BATES, OF CHICAGO, ILLINOIS.

METHOD OF MAKING TRUSSED STRUCTURES.

1,005,925.

Specification of Letters Patent. Patented Oct. 17, 1911.

Original application filed April 18, 1910, Serial No. 556,221. Divided and this application filed September 23, 1910. Serial No. 583,394.

To all whom it may concern:

Be it known that I, ALBERT J. BATES, a citizen of the United States, residing at Chicago, in the county of Cook and State of Illinois, have invented certain new and useful Improvements in Methods of Making Trussed Structures, of which the following is a specification.

This is a division of my application Serial No. 556,221, filed April 18, 1910, and the invention relates to the formation of an integral metallic structure having longitudinally extending side members spaced apart and connected at intervals throughout their length by truss members which are preferably angularly disposed to the side members.

So far as I am aware, trussed structures heretofore employed in the construction of buildings, bridges, elevated railways and other metal work, have been built up of longitudinal side members connected together by cross pieces riveted or bolted thereto.

My invention aims to obviate the necessity of building up structures of this kind from separate parts by converting a solid bar or strip of metal into a skeleton structure having all of its parts embodied in an integral formation of the same or substantially the same length as the original bar or strip, thus producing a trussed structure with a certain inherent elasticity and consisting essentially of longitudinal side members and transverse truss members angularly disposed with relation to the side members to form a plurality of adjacent triangular-shaped openings in the structure. In the formation of the structure the side members remain substantially unchanged in shape, length and thickness, but the truss members are stretched lengthwise and more or less reduced in cross section. By this method I am enabled to produce a structure much stronger than the built-up structures heretofore employed and free from the weaknesses at the joints of the parts in the old structures; and, furthermore, my integral structure is much more rigid and durable than a built-up structure, in which there is the constant liability of bolts or rivets working loose or being sheared off.

Another object of my invention is the production by a simple and inexpensive method of a structure in which the strains and stresses are distributed evenly throughout its length, which desideratum is practically

impossible in built-up structures because of the inevitable inaccuracies which creep into an attempt to make a large number of pieces of exactly the same length or to drill or punch a large number of holes which shall be spaced exactly the same distance apart.

My invention also aims to produce a structure which shall be light in weight, which can be manufactured at low cost, and which is capable of a variety of uses to which a built-up structure could not be successfully adapted.

Additional aims and objects of my invention will be apparent to those skilled in the art as it becomes better understood by reference to the following description in connection with the accompanying drawings illustrating the invention.

Referring to the drawings, Figure 1 is a plan of a bar or strip of metal from which my improved structure is made. Fig. 2 is a plan of this bar after grooving and slitting operations have been completed. Fig. 3 is a plan showing the side members of the bar partially separated. Fig. 4 shows side sections separated to produce a trussed structure of maximum strength. Fig. 5 is a section on the line 5—5 of Fig. 4. Fig. 6 is a section on the line 6—6 of Fig. 2. Figs. 7 to 10 are views similar to Fig. 6 showing other forms of bar. Fig. 11 is a view similar to Fig. 2, but having slits therein of graduated lengths to produce a tapering structure. Fig. 12 shows the resulting structure after the side members of Fig. 11 have been separated. Fig. 13 is a side view of an I-beam slitted according to my invention. Fig. 14 shows a method of connecting two of my improved trussed structures. Fig. 15 is a section on the line 15—15 of Fig. 14. Fig. 16 is a section on the line 16—16 of Fig. 13. Fig. 17 shows a tool constructed to engage with the side members of a slitted bar for the purpose of separating them. Fig. 18 shows my invention employed as a fence post.

In practicing my invention I provide a bar or strip or beam 17 which may be made in many different forms in cross-section. In Fig. 6 the bar is provided with grooves or longitudinal depressions 18 near its edge which form grip surfaces so that the bar can be firmly grasped by a tool or machine for the purpose of separating the side members, as will be later described. The grip surfaces may be otherwise pro-

duced, as by the flanges 19, (Fig. 7), the 5 grooves 20, (Fig. 8), the beads 21, (Fig. 9), the ribs 22 (Fig. 10), or the side members may be roughened to insure proper engagement by the tool. Instead of forming these gripping surfaces on the bar, the drawing or stretching means may be provided with suitable gripping surfaces to make locking engagement with the bar.

10 The bar, with or without the gripping surfaces, is provided with a plurality of slits 23 extending longitudinally throughout its length and in staggered relation to each other and in two series. These slits, as 15 shown in Fig. 2, are of substantially equal length, the ends of the slits being separated by an integral tie portion 24 affording sufficient strength to prevent fracture during the separating or drawing operation. The 20 uncut tie portions 24 between the slits in each series are preferably disposed substantially opposite the center of the slits in the other series, and each series of slits is located substantially equidistant from the edges of 25 the bar and from each other, thus dividing the bar into two longitudinal side members 25, 26, and an intermediate member 27. The slits may be produced by any suitable cutting implement with the bar in either heat- 30 ed or cold condition, as may be found desirable.

After the slitting operation, the side members of the bar are grasped throughout their length, or at such points as may be found 35 practical and sufficient, by a suitable stretching tool or implement. Any preferred type of stretching or drawing device may be employed, one type being shown in Fig. 17 for the purpose of illustration merely. The 40 device shown comprises jaws 28 adapted to engage the previously described gripping surfaces on the side members. Suitable means are employed for pulling the jaws to 45 separate the side members and to stretch or elongate the sections 29 of the intermediate member of the bar into a sinuous form, as shown in Fig. 3, without increasing or decreasing the length of the side members. The pulling or stretching operation is materially facilitated by heating the bar, and 50 in heavy work the heating of the bar is practically necessary.

The structure thus produced and as 55 shown in Fig. 3 may be employed for numerous purposes, but the form which gives the maximum strength and efficiency is disclosed in Fig. 4, wherein the side members 25 and 26 have been separated until the sections 30 of the intermediate member 27 connecting the tie portions 24, are straight and disposed at practically an angle of 60° with the side members. In thus forming the structure the side members are neither changed in length nor in thickness, and they 60 are trussed and strengthened by the angu-

larly disposed sections of the intermediate member. The side members and the elongated sections of the intermediate member form an integral structure having a plurality of adjacent triangular openings, the 70 sides of these triangles being formed by the sections and the bases thereof by the side members. The triangles are arranged with their bases alternating between the side members.

75 In the structure shown in Figs. 1 to 8, inclusive, the slits in the bar have been made of uniform length and the side members have been drawn apart and maintained in substantial parallelism. If it is desired to produce a tapering trussed structure, such as is disclosed in Fig. 12, the slits 31 are graduated in length from one end of the bar 32 to the other (Fig. 11). When the stretching operation is performed the longer slits 85 at one end of the bar will permit the side members 33 and 34 to be separated farther than will the shorter slits near the other end of the bar. This structure, shown in Fig. 12, is particularly adapted for use in aerial 90 structures, such as towers, etc., and as telegraph, telephone or power poles.

In Figs. 13 and 16, I have shown an I-beam 35 slitted for stretching to form a trussed structure adapted for use in building construction, as shown in Figs. 14 and 15. In the latter figures there is shown a girder 36 and an upright 37, the connection being made by suitable angle-bars 38 and rivets 39 such as are ordinarily employed in 100 constructions of this kind. It will be obvious that a building frame constructed as shown in Fig. 14 may be made much lighter and stronger than a frame fabricated of the same material in built-up form. A frame of 105 this kind is also particularly adapted for use in concrete constructions, the concrete uniting with the open work of the structure to form a firm and substantial mechanical bond.

110 My invention may also be employed as a fence post, as shown in Fig. 18, wherein the lower end of the post 40 is embedded and rigidly held in concrete 41 or other suitable material. The wires 42 of an ordinary wire 115 fence may be attached to the post by clips 43 or other preferred means. A post thus constructed is strong and durable, and offers the greatest resistance along a line transverse to the direction of the wires of the 120 fence. This is a most useful and efficient type of post since the strain upon the fence is usually exerted against the side thereof which will be resisted by the post made as herein described and set as shown in Fig. 18. 125

130 It will be obvious from the foregoing description that the structures produced by my invention, as above described, are capable of a variety of uses both in structural work and in reinforced concrete work. Furthermore

they may be employed in lighter constructions such as telephone poles or fence posts, hitching posts, etc., and in fact constitute a very cheap and efficient substitute for either the built-up or solid constructions heretofore employed.

This invention has the additional advantage that the resultant structure is of the same length as the original bar from which it is made and the side members are of their original length and cross section, the stretching taking place only in the diagonal members between the side members. Thus my novel method provides for changing a bar or strip or beam into a skeleton form with the parts integrally connected and disposed in a manner to provide maximum strength, rigidity and efficiency.

While I have shown and described several forms of structures produced in accordance with my invention, it will be apparent that these forms are selected for the purposes of illustration merely and that many other forms may be produced if desired.

What I claim and desire to secure by Letters Patent is:

1. The method of making a trussed metal structure from a single piece of ductile metal, such as a bar, which consists in forming a series of slits intermediate of and substantially parallel to the marginal portions of the bar, and then separating the unsevered side members without substantially changing their length, and stretching the intermediate members thereby increasing their length and producing an angular relation thereof with respect to the side members.

2. The method of making a trussed metal structure which consists in forming inter-

mediate the marginal portions of a bar or blank a series of slits substantially parallel to said marginal portions and in staggered relation to each other, and then separating the marginal portions without material elongation and stretching the portions between the slits thereby elongating them and producing an angular relation of the elongated members with reference to the marginal members and with reference to each other.

3. The method of making a trussed metal structure from a bar having marginal flanges which consists in forming in the web portion of said bar a series of slits substantially parallel to the margins and staggered with relation to each other and then separating the marginal portions in the plane of the web thereby elongating the portions of the metal between the slits without substantial elongation of the marginal members or lateral distortion of any of said members.

4. The method of making a trussed metal structure from a single piece of ductile metal which consists in slitting the metal intermediate its side margins, the slits being substantially parallel to said margins and in staggered relation to each other, and then while the metal is hot laterally separating the side margins without substantially changing their length while stretching the metal between the slits, thereby producing a zig-zag relation of the intermediate portions with relation to each other and to the side margins.
